UNITED STATES PATENT OFFICE.

JAMES E. JEWELL, OF KANSAS CITY, MISSOURI.

SELF WEIGHING AND SACKING MACHINE.

1,386,506.

Specification of Letters Patent.

Patented Aug. 2, 1921.

Application filed July 21, 1919. Serial No. 312,224.

To all whom it may concern:

Be it known that I, JAMES E. JEWELL, a citizen of the United States, residing at Kansas City, in the county of Jackson and 5 State of Missouri, have invented certain new and useful Improvements in Self Weighing and Sacking Machines, of which the following is a specification.

This invention relates to self weighing and 10 sacking machines, and is designed more especially for handling potatoes and the like in retail establishments, such as grocery stores, so that the work of the salesman shall be expedited and the necessity of touching 15 the potatoes with his hands shall be avoided.

The object of the invention is to produce a machine of the character set forth which is efficient and accurate in operation, sanitary, and can be manufactured at low cost.

20 With this object in view, the invention consists in certain novel and useful features of construction and combinations of parts as hereinafter described and claimed; and in order that it may be fully understood reference is to be had to the accompanying drawings, in which:—

Figure 1, is a front elevation of a self weighing and sacking machine embodying the invention.

30 Fig. 2, is a view showing the machine in central vertical section except the weighing element thereof, which is in vertical section near one end to avoid the necessity of illustration of the internal mechanism of said element which may be of any approved suspension type.

Fig. 3, is a top plan view of the machine.

Fig. 4, is a horizontal section on the dotted line IV of Fig. 1.

40 Fig. 5, is a vertical section of the weighing box or receptacle of the machine.

Referring now to the drawings, in detail, 1 indicates the four legs of the machine, corresponding front and rear legs being connected at their inner edges by the brace bars 2, which in turn are connected near their front ends by a cross brace 3, a parallel cross brace 4 connecting the front ends of braces 2 and the front legs 1. The latter are also connected at their upper ends by a cross brace 5.

50 The bin or hopper of the machine consists of the sides 5^a, back 6, inclined bottom 7 and the front wall, the latter comprising the vertical portion 8 having a discharge opening in its lower end as at 8^a, for the contents of the bin, and an upper portion 9 extending up-

wardly and forwardly to a vertical plane between braces 3 and 4, and notched at its upper corners at 10, for the accommodation of vertical frames forming the sides of the 60 space for the weighing elements, said frames consisting of bars 11 and 12, secured together and the former to the sides 5^a and bars 12 to the rear edges of the front legs, the bars 11 being spaced slightly forward of the vertical portion 8 of the bin or hopper to provide the interposed vertical grooves 13 for the play of the slide door or gate 14, controlling the discharge opening 8^a of the bin.

Secured to and depending below the plane 70 of the cross brace 5, and disposed at the rear side of the same, is a cross piece 15, and fitting vertically between the vertical frames mentioned and at the rear side of said cross piece, is a rectangular frame 17 through 75 which the weighing markings are observable, said frame 17 having depending extensions 18, through which fastening devices extend into the sides 12 for retaining the rectangular frame in position.

80 Fitting against the rear side of frame 17, is a weighing scale inclosing frame, consisting of uprights 19, horizontal top and bottom pieces connecting the uprights and respectively numbered 20 and 21, and intermediate 85 vertical uprights 22 as the more direct support for the face plate 23 of the scale mechanism, said plate having the customary dial markings and an index finger 24 for cooperative relation to said markings. The 90 upper cross bar of the weighing scale inclosing frame, is extended laterally and rests upon the upper ends of the bars 12, which thus serve as a support for the scale inclosing frame, the bar 20 being supported intermediate 95 its ends, upon the wall portion 9.

Pivotedly suspended at 25 from the scale, 100 is a cross bar 25^a having downwardly extending suspension rods 26 at its ends, carrying a box or receptacle 27; the rods extending through the end walls of the box and being engaged at their lower ends by retaining nuts 28. The box has a hinged dumping bottom 29, pivotally connected at one end by a link 30 to a lever 31, by which the bottom can be easily reëlevated to closed position after each dumping operation, the 105 said lever having a laterally-projecting handle 32 at its free end for engaging the upper edge of the box when the bottom thereof is properly closed. In the front edge of the bottom of box 27, is a notch 33, and verti-

cally above said notch bearings 34 secured to the front wall of the box, accommodate a rotatable rod 35, which extends through said notch and is provided at its lower end 5 with a crank or locking arm 36, and at its upper end with a crank or operating handle 38. When the rod 35 is positioned as shown in Figs. 1 and 2, its cranks or arms project laterally, and the crank 36 underlies 10 and holds the dumping bottom closed and the upper crank avoids interfering with the entrance of potatoes into the box, when the slide door or gate 14 is opened. By turning the operating handle 38 through a half circle, the dumping bottom is unfastened and free to swing down to open position and discharge its contents into and through the flexible funnel 39, to a sack or basket, not shown, for the convenience of the customer. 15 For easily effecting the opening and closing movements of the slide door or gate 14, a hand lever 40 is hinged to the front wall of the bin, and said lever is hingedly linked as at 41 to said door or gate. 20 When the gate is opened, potatoes fall into the box until the same is full or the discharge is checked by closing of the gate. The scale is watched and as the desired quantity of potatoes is thus obtained and the 25 supply cut off, the operator operates the locking rod 35 to release the bottom and effect the dumping of the contents of the box, as above explained. The lever 31 is then operated to reclose the bottom and thereby 30 set the machine for the next operation. 35 From the above description it will be apparent that I have produced a machine embodying the features of advantage set forth as desirable in the statement of the object of 40 the invention, and while I have illustrated and described the preferred embodiment of the same, it is to be understood that I reserve the right to make such changes as properly fall within the principle of con-

struction involved, and the scope of the ap- 45 pended claims.

I claim:

1. A self weighing and sacking machine comprising a hopper having a front discharge opening, a vertically slidable door 50 controlling said opening, a weighing device secured forward of the upper portion of the hopper, a bar pivotally suspended from the weighing device, a pair of rods depending from said bar, a receptacle secured to the lower ends of said rods, a hinged dumping bottom for said receptacle, a rock shaft having a crank arm for underlying and holding the bottom of the receptacle in closed 55 position, and lever-actuated means for limiting the opening movement and for effecting the closing movement of said bottom.

2. A self weighing and sacking machine comprising a hopper having a front opening, legs supporting said hopper, vertical 60 bars secured to the inner sides of the hopper forward of the front wall thereof to provide interposed grooves, a vertical door 65 slidable in said grooves for controlling said discharge opening, bars secured to the first- 70 named bars inward of the side walls of the hopper, a frame between the last - named bars, a weighing device fitting between said last-named bars and against the inner side of said frame, and provided with a cross bar 75 resting upon the upper edge of the front wall of the hopper and the second pair of bars mentioned, a vertically movable receptacle forward of the hopper and below the plane of the discharge opening thereof and 80 suspended from said weighing device, a funnel depending from said receptacle, a dumping bottom for the receptacle, and manually operable means for holding the bottom in closed position.

In testimony whereof I affix my signature.

JAMES E. JEWELL.
